UNITED STATES PATENT OFFICE.

PEDRO BERNAL, OF HONOLULU, TERRITORY OF HAWAII.

SPARK PLUG.

Application filed February 6, 1925. Serial No. 7,387.

This invention relates to improvements in spark plugs.

An object of the invention is to provide a spark plug having renewable electrodes.

5 It is also an object of the invention that the improved spark plug be constructed to prevent accumulation of carbon.

It is also an important object of the invention that the improved spark plug be 10 "sturdy" in construction, easy to assemble or disassemble when renewing the electrodes, and inexpensive to manufacture.

The invention is illustrated by way of example in the accompanying drawings, in 15 which:

Figure 1 is a perspective view of the spark plug,

Figure 2 is a vertical sectional view of the same,

20 Figure 3 is a sectional view taken substantially on line 3—3 of Figure 2, and,

Figure 4 is a group view showing in perspective the insulated electrode and its associated conductor elements.

25 Referring to the drawings more particularly, 10 indicates a spark plug shell, 11 the insulator element of the spark plug, and 12 the usual threaded bushing for securing the insulator element 11 within the shell 10.

30 The lower end bore portion 13 of the shell 10 is of less diameter than the bore portion 14 thereby providing a shoulder 15. The insulator element 11 fits tightly within the bore portion 13. The insulator 11 is provided with an annular enlargement 16 which seats upon the shoulder 15, and a packing washer 17 is interposed between the enlargement 16 and shoulder 15. The shell 10 has its lower end portion provided with a bore

35 17' adapted to receive the electrode 18. The electrode 18 is in the form of an elongated pin terminating at one end in a head 19 which is preferably provided with a screw driver slot 20. It will be noted the head 19 is beneath the washer 17 and the electrode 18 is rigidly held against movement by the bushing 12, said bushing being threaded into the bore portion 14 of the shell as shown. Preferably, a washer 21 is interposed between the bushing 12 and enlargement 16 of the insulator element.

40 The insulator element 11 has its upper end formed with a central longitudinal bore which accommodates the electrode 22. The 45 bore accommodating electrode 22 is enlarged at its upper end as at 23, and into this en-

larged bore portion there is threaded a nipple extension 24 of a "connector-plug" 25. This member 25 is seated upon the associated end of the insulator element as shown, and if desired, the nipple 24 may be cemented within the insulator element in order to 50 form a durable connection therewith.

The "connector-plug" 25 is provided with a longitudinally extending bore which is 55 adapted to receive the electrode 22, and said bore terminates at its outer end in an enlargement 26 which is threaded as shown and adapted to receive the threaded portion 27 of a binding post 28. The post 28 has a 60 reduced threaded portion 29 which carries a binding nut 30.

It will be noted that the electrode 22 is similar in structure to the electrode 18 viz; it terminates at its one end in a head 31 75 which is provided with a screw driver slot. Preferably the head 31 is counter-sunk in the insulator element 11 as shown. The head 19 of electrode 18 is also counter-sunk in the shell 10, Figure 2.

70 Between the head 31 of electrode 22 and post 28 there is interposed a plate 32 to insure good contact between the electrode and the post.

It is important to observe that the electrodes 18 and 22 extend a considerable distance below the shell and thus providing a considerable length of said electrodes between which sparks can occur. Also by permitting the electrodes to depend a considerable distance below the shell and maintaining the same straight as shown, minimizes the accumulation of carbon upon the electrodes in an obvious manner.

85 If it is desired to renew either of the electrodes 18 or 22, the same can be accomplished in a short interval of time. The manner in which the electrodes can be removed and replaced is thought to be entirely obvious and therefore a detail description 90 thereof would seem unnecessary. It might be noted that before attempting to withdraw either of the electrodes, a screw driver might be used to loosen the same.

95 While I have shown and described the preferred form of my invention, I wish it to be understood that I am aware of the fact that the general construction, combination and arrangement of parts, might be changed by those skilled in the art without departing from the spirit of my invention as indicated by the appended claims.

I claim:—

1. In a spark plug construction an insulator element, a metallic extension, fixed in the outer end thereof, an elongated pinlike electrode extending centrally and longitudinally through the insulator element and metallic extension, said electrode being freely removable and said metallic extension having a bore enlargement at its outer end, a head formed upon the outer end of the pin electrode and disposed in said bore enlargement, and a metallic terminal post threaded into the bore enlargement of said metallic extension and seating the head of said pinlike electrode.
2. In a spark plug construction an insulator element, a metallic extension, fixed in

the outer end thereof, an elongated pin-like electrode extending centrally and longitudinally through the insulator element and metallic extension, said electrode being freely removable and said metallic extension having a bore enlargement at its outer end, a head having a screw driver slot formed upon the outer end of the pin electrode and disposed in said bore enlargement, a metallic terminal post threaded into the bore enlargement of said metallic extension and seating the head of said pin-like electrode, and a metallic plate interposed between the head of said electrode and associated end of terminal post.

PEDRO BERNAL.
